UNITED STATES PATENT OFFICE

159,788

SEAPLANE

William K. Ebel, Columbus, Ohio, and John D. Pierson, Overlea, Md., assignors to The Glenn L. Martin Company, Middle River, Md., a corporation of Maryland

Application February 4, 1949, Serial No. 674

Term of patent 14 years

(Cl. D71—1)

To all whom it may concern:

Be it known that we, William K. Ebel and John D. Pierson, citizens of the United States of America and residents, respectively, of Columbus, county of Franklin, State of Ohio, and Overlea, county of Baltimore, State of Maryland, have invented a new, original, and ornamental Design for a Seaplane, of which the following is a specification, reference being had to the accompanying drawings, forming a part thereof.

Figure 1 is a side perspective view of a seaplane showing the hull and empennage assembly.

Figure 2 is a bottom perspective view thereof.

Figure 3 is a top plan view thereof.

Figure 4 is a front elevational view thereof.

Figure 5 is a side elevational view thereof.

The characteristic features of our design reside in the portions shown in full lines in the drawings.

We claim:

The ornamental design for a seaplane, substantially as shown and described.

WILLIAM K. EBEL.
JOHN D. PIERSON.
